UNITED STATES PATENT OFFICE.

ROBERT A. GULLION, OF GALLATIN, TEXAS.

AUTOMATIC RAILWAY-SWITCH.

1,254,403.

Specification of Letters Patent. Patented Jan. 22, 1918.

Application filed July 12, 1916. Serial No. 108,890.

To all whom it may concern:

Be it known that I, ROBERT A. GULLION, a citizen of the United States, residing at Gallatin, in the county of Cherokee and State of Texas, have invented certain new and useful Improvements in Automatic Railway-Switches, of which the following is a specification.

This invention has relation to automatic railway switches, and the nature and objects thereof will be readily apparent to those skilled in the art to which it appertains, in the light of the following explanation of the accompanying drawings, illustrating what I now believe to be the preferred embodiment or mechanical expression of my invention, from among other forms and arrangements within the spirit thereof, or the scope of the appended claims.

20 However, an object of the invention is to provide means disposed at the side of a railway track, and operable by a projection on the locomotive to actuate the switch points of a switch frog controlling communication 25 to a siding whereby the train is permitted to enter the siding when the mechanism is actuated, said mechanism being also actuatable by a projection upon the locomotive when the train is backed out of said siding.

30 Another object of the invention is to provide means on the locomotive for actuating the switch mechanism mentioned above, said means comprising relatively movable tripping arms adapted to extend from opposite 35 sides of the locomotive, and having a novel actuating means operable from the engineer's cab.

In addition to the foregoing, my invention comprehends improvements in the details of 40 construction and arrangements of parts, to be hereinafter described and particularly set forth in the appended claim.

In the accompanying drawings, in which similar and corresponding parts are designated by the same characters of reference throughout the several views in which they appear:

Figure 1 is a view in plan of a section of 50 railway track and switch points, illustrating the application of my invention thereto.

Fig. 2 is a detail view in plan of the tripping arms of the locomotive, and actuating means therefor.

Fig. 3 is a detail view in perspective of

the upper portion of my improved switch stand, and

Fig. 4 is a detail view of means employed in connection with my invention for transmitting motion from the switch stand to the switch points.

Fig. 5 is a detail view showing the manner in which a roller is mounted.

With reference to the drawings, 1 indicates the rails of a section of track, and 2 the switch points of a switch frog, pivoted at 3, whereby the said switch points may be moved relatively to the rails to direct the flanges of the car wheels either along the main track or into the siding as the case may be. The switch points are connected by means of a brace 4 to insure their movement in unison.

That portion of my invention relating to the operation of the switch points comprises a switch stand 5, built after the manner of the conventional switch stand, secured by means of bolts or the like 6 to cross ties 7, and having at its upper portion an annular upstanding flange 8. A vertically extending post 9 is mounted for rotation centrally of the switch stand, and adapted for slight vertical movement. The post 9 is provided at its upper portion with the usual vanes 10 for indicating to the engineer of an approaching train the position of the switch points, and at its intermediate portion, just above the flange 8, with a lateral arm 11, extending at right angles from the post 9, and having its outer end bifurcated to form trip fingers 12 disposed in relative angular relation and in the same horizontal plane. The arm 11 is adapted to rest upon the upper edge of the flange 8, and is provided at the point of contact with a roller 13. The flange 8 of the switch stand is formed at points 14 having upwardly diverging sides 15, for a purpose to be presently noted.

The switch stand is located at a convenient distance from the near side of the switch points, and is adapted to actuate the switch points by means of an intermediate mechanism comprising a vertical stub shaft 16, journaled in a circular base 17 which is located to one side of the track rails directly opposite the switch points, the lower end of said shaft having an arm 18 which is connected by means of a link 19 to one of

the switch points. The upper end of the shaft 16 is provided with an arm 20, which is however disposed in angular relation relative to the arm 18, and is connected by means 5 of a link 21 to an arm 22 located on the lower terminal of the post 9 of the switch stand.

Upon the forward portion of a locomotive, illustrated to some extent in Fig. 1, directly 10 above the cow catcher 23 thereof, I provide oppositely extending trip arms 24, relatively movable and mounted for movement transversely of the locomotive in brackets 25. The outer terminals of the arms 24 are provided with bearing members 26 adapted to support rollers 27 for rotation about a vertical axis 28. A toothed segment 29 is mounted for rotation at 30, beneath the arms 24 and in alinement with the longitudinal 15 center of the locomotive, and is formed with a diametrically opposite radial arm 31. The arm 30, and the segment 29 are connected by means of links 32 to the arms 24, whereby rotation of the segment in either direction 20 will cause sliding movement of the arms toward or away from each other. A shaft 33 is provided centrally of the locomotive, with a pinion 34 at its forward end for meshing engagement with the toothed segment 29, 25 and having at its rear end certain mechanism (not shown) for rotating the shaft from the engineer's cab.

The mode of operation of my invention is as follows: The engineer of a train approaching the switch points, desiring to enter the siding, operates certain mechanism at his command whereby the shaft 33 is rotated, thereby rotating the segment 29 in a clockwise direction, and extending the arms 24 30 beyond the sides of the locomotive through the medium of the link connections. With the right arm 24 in extended position, one of the fingers 12 of the switch arm 11 will be directly in the path of movement of the roller 27 of said arm. When the said finger is contacted by the roller 27, the arm 11 is given an impact which causes the roller 13 thereof to ride out of the notch 14 in which the roller is normally disposed, and the arm 50 is moved until the said roller is engaged in

the other of said notches 14. The post 9 is obviously rotated by the arm 11, and the shaft 16 is also rotated through the medium of the link 21 thereby shifting the switch points relative to the track rails so as to 55 guide the car wheel flanges into the siding.

It will be obvious that the arm 11 having been moved approximately 45°, the finger 12 thereof opposite the one previously engaged, will be extended out toward the track 60 rail. The engineer then, upon leaving the siding by backing out, will engage the said finger 12 by means of the arm 24 and the arm 11 will be returned to its original position, thereby resetting the switch points. 65

While I have illustrated and described my invention with some degree of particularity, I realize that in practice various alterations thereover may be made, and I therefore reserve the right and privilege of changing 70 the form of the details of construction, or otherwise altering the arrangement of the correlated parts, without departing from the spirit of the invention or the scope of the appended claim. 75

Having thus fully described my invention what I claim as new and desire to secure by Letters Patent, is:—

The combination with a railway track including movable switch points, of a switch stand having an annular vertically extending flange provided with angularly spaced notches, a vertical post journaled for rotation concentrically of said flange, an arm on the post adapted to contact with the flange and to normally be engaged in one of the said notches, a roller on the arm at the point of contact, said arm being engageable by a projection upon a passing locomotive to cause the roller to ride out of the notch thereby moving the arm and rotating the post, permitting the roller to drop into the other notch, and means operable by rotation of the post to move the switch points.

In testimony whereof I affix my signature in presence of two witnesses.

ROBERT A. GULLION.
